COIL HANDLING APPARATUS

Earll R. Muddiman, Wilkinsburg, Pa., assignor to
United States Steel Corporation, a corporation
of New Jersey

Application July 11, 1947, Serial No. 760,326

9 Claims. (Cl. 242—79)

1

This invention relates to apparatus for handling sheet metal coils during processing, and particularly to apparatus for positioning coils for engagement by uncoiling mandrels.

An object of the invention is to provide improved handling apparatus for mechanically positioning coils for engagement by uncoiling mandrels, irrespective of varying outside coil diameters.

Further objects of the invention are to provide handling apparatus having improved mechanism for elevating coils and automatically stopping vertical movement at mandrel level, and to provide improved apparatus facilitating further processing, such as temper rolling, of coils with less likelihood of coil damage.

In accomplishing these and other objects of the present invention, I have provided improved structural details, preferred forms of which are shown in the accompanying drawings, wherein:

Figure 1 is a top plan view of a coil handling apparatus embodying features of the present invention, and installed between the entry ramp and uncoiling mandrels, such as those preceding a temper rolling stand;

Figure 2 is a vertical sectional view of the apparatus taken substantially on line II—II of Figure 1;

Figure 3 is a vertical sectional view of the lower portion of the apparatus taken substantially on line III—III of Figure 1;

Figure 4 is a vertical sectional view taken substantially on line IV—IV of Figure 1 and showing one form of mechanism for stopping vertical movement when the coil is at mandrel level; and

Figure 5 is a schematic view of a modified mechanism for similarly stopping vertical movement.

Referring more in detail to the drawings:

In Figure 2 there is shown at 10 an inclined entry ramp substantially at floor level on which coils 11 of sheet metal are placed by suitable handling or conveying mechanism. The entry ramp includes the usual retractible stop 12, which restrains coil movement until it is desired to place a coil on the uncoiling mandrels, designated 13. Said mandrels are of any usual construction, but ordinarily include retractible fingers 14 engageable with the inside of coil 11. The mandrels are rotatable on a fixed horizontal axis, and in temper mills have mechanism for restraining rotation and thereby tensioning the strip. The equipment thus far described is conventional and hence is not described in greater detail.

2

The apparatus of the present invention handles coils between entry ramp 10 and mandrels 13 and comprises a cradle 15 supported on a carriage 16, preferably located in a pit 17 beneath floor level. Mechanism is provided for moving said cradle vertically and horizontally to convey coils from ramp 10 to mandrel engaging position. The cradle has a downwardly sloping section 19 and upwardly sloping sections 20 and 21, Figure 2. When the cradle is in position to receive a coil from entry ramp 10 (the dotted line position of Figure 2) section 19 forms a continuation of said ramp. On retraction of stop 12, a coil rolls from ramp 10 onto the cradle.

Carriage 16 includes a horizontally movable, vertically fixed outer box 22. Said box is supported within pit 17 on guides 24 which constrain carriage movement to a horizontal path. A rearwardly extending floor plate 25 is affixed to the upper edge of box 22 to cover the pit 17. The guides preferably include flanged wheels 26 rotatably mounted on the carriage and riding on rails 27 fixed to shelves on the sides of the pit, as best shown in Figures 2 and 3. Preferably hydraulic or pneumatic piston and cylinder means 28 are provided for moving the carriage, although the invention is not limited to any particular motive means.

An inner box 29 is mounted within outer box 22 for relative vertical movement. Cradle 15 is supported at the top of box 29. A pair of extensible supply pipes 30 are supported in the pit and are connected to a hydraulic or pneumatic cylinder 31. Said cylinder is fixed within outer box 22 and contains a piston 31. Said piston is connected with inner box 29 by a flange 32 on the piston and a bracket 33 on said inner box, whereby the inner box, cradle and a coil thereon are raised or lowered on piston movement.

After a coil has been placed on the cradle, as shown in the dotted line position of Figure 2, said cradle is elevated to locate the coil center at mandrel level, which is somewhat higher than the level of the entry ramp, or of the cradle at this position. Since there is variation in coil outside diameters, positioning is in accordance with the inside of the coil. Means are provided for automatically stopping vertical movement when the coil reaches mandrel level.

As best shown in Figures 1 and 4, one form of stop means includes a pair of vertically disposed guides 34 and 35 supported adjacent the cradle. A horizontally extending cylinder 36 is mounted on said guides for relative vertical movement. A limit switch 37 is fixed to said guides above said cylinder in position to be actuated on upward

movement of the cylinder. The cylinder contains an extensible and retractable spindle 38 adapted for projection within the coil central opening.

After a coil is placed on the cradle, spindle 38 is projected. The cradle and coil are lifted by operation of piston 31 in cylinder 30. The lower inside face of the coil engages spindle 38 and lifts said spindle and cylinder 36, until the latter actuates limit switch 37. Actuation of the switch stops upward movement of the coil, any suitable mechanism being provided for the purpose, as, for example, a solenoid 60 and a valve 61 operated by said solenoid and situated in the fluid line to cylinder 30, as shown schematically in Figure 2. The design is such that limit switch 37 is actuated when the coil reaches mandrel level. Following switch actuation, spindle 38 is retracted.

After being raised, carriage 16 is moved forward horizontally by actuation of piston and cylinder means 28. A flanged stop 39 in the path of the carriage stops horizontal movement when the coil is vertically aligned with the mandrels, the full line position of Figure 2.

The mechanism just described thus aligns the coil axially with mandrels 13. The latter may be projected into the coil and fingers 14 extended to engage and support the coil for unwinding. After the mandrels engage the coil, cradle 15 is lowered and its horizontal movement reversed, being thereby returned to the dotted line position of Figure 2. While the coil on the mandrels is unwinding, another coil may be placed on cradle 15 and elevated ready to be moved forward to mandrel engaging position.

Figure 5 shows schematically a modified construction wherein photoelectric means are employed for stopping cradle vertical movement. As shown in Figure 5, a light source 51 is provided for projecting a beam through the coil central opening. A photoelectric cell 52 is mounted at the opposite side of the coil in a position to be energized by light source 51. As the coil is raised, it reaches a position where the path between light source 51 and cell 52 is interrupted by the coil material. The circuit through the cell is thereby broken, opening switches of photoelectric relay 53. This action corresponds to actuation of limit switch 37 and causes vertical movement to cease through any suitable mechanism.

It is seen that the present invention provides handling apparatus that mechanically positions coils accurately for mandrel engagement. Coil handling is thus greatly facilitated, and coil damage caused by mandrel engagement is minimized due to accurate placement of the coils before such engagement.

While I have shown but certain embodiments of the invention, it is apparent that further modifications may arise. Therefore I do not wish to be limited by the disclosure set forth, but only by the scope of the appended claims.

I claim:

1. Apparatus for handling coils of sheet material comprising a carriage, a cradle mounted on said carriage for relative vertical movement, means in said carriage for elevating said cradle, and means for stopping said elevating means when a coil on said cradle reaches a predetermined level, said stop means including a spindle adapted to be projected into the coil opening and being engageable with the wall of the opening, means mounting said spindle for relative vertical movement, and a limit switch with which said

spindle mounting means is engageable for stopping actuation of said elevating means.

2. An apparatus for transferring coils of strip material from an entry ramp to a rotatable uncoiling mandrel comprising a cradle adapted to receive coils from the ramp, means for elevating said cradle, a stop adapted to act on the portion of a coil body adjacent the central opening thereof for automatically stopping upward movement of said cradle when a coil thereon attains mandrel level, and means for moving said cradle horizontally toward the mandrel and thus in a single horizontal motion positioning a previously elevated coil for engagement by the mandrel.

3. An apparatus for transferring coils of strip material from an entry ramp to a rotatable uncoiling mandrel comprising a carriage supported for horizontal movement in a direction perpendicular to the axis of rotation of the mandrel, a cradle supported on said carriage for relative vertical movement and adapted to receive coils from the ramp, means for elevating said cradle after it has received a coil, a stop adapted to act on the portion of a coil body adjacent the central opening thereof for automatically stopping upward movement of said cradle when a coil thereon attains mandrel level, and means for moving said carriage and said cradle horizontally toward the mandrel after said cradle has been elevated and thus in a single horizontal motion positioning a previously elevated coil for engagement by the mandrel.

4. The combination with an entry ramp and an uncoiling mandrel which is spaced longitudinally from the terminus of said ramp, and is rotatable on a horizontal axis, of an apparatus for transferring coils of strip material from said ramp to said mandrel comprising a carriage supported for horizontal movement between said ramp and a point beneath said mandrel, a cradle supported on said carriage for relative vertical movement, said carriage and said cradle having a position in which said cradle forms a continuation of said ramp for receiving a coil therefrom, means for elevating said cradle after it has received a coil and while the preceding coil is still on said mandrel, a stop adapted to act on the portion of a coil body adjacent the central opening thereof for automatically stopping upward movement of said cradle when a coil thereon attains mandrel level, and means for moving said carriage and said cradle horizontally to a position under the mandrel axis after said cradle has been elevated and the preceding coil exhausted and thus in a single horizontal motion positioning the new coil for engagement by said mandrel.

5. An apparatus as defined in claim 2 in which said stop includes a spindle adapted to project into the central opening of a coil and to engage the coil body adjacent the central opening thereof when said cradle is elevated and a limit switch operated by said spindle on engagement by the latter with the coil.

6. An apparatus as defined in claim 2 in which said stop includes a light source adapted to cast a beam through the coil opening, a photoelectric cell on the opposite side of the coil opening adapted to be de-energized when the coil body adjacent the central opening thereof interrupts the beam, and a switch operated by said photoelectric cell on de-energization thereof.

7. A power-driven automatic locating gear for locating a load relatively to a predetermined axis comprising a base frame, a cradle movable relatively to said frame and serving to receive

the load, gauging means arranged to assess the relevant dimensions of said load upon said cradle, operating means for moving said cradle, and control means responsive to said gauging means for causing said operating means to locate the load relative to the predetermined axis.

8. A power-driven automatic locating gear for locating a load relatively to a predetermined axis comprising a base frame, a cradle movable relatively to said frame and serving to receive the load, gauging means arranged to assess the relevant dimensions of said load upon said cradle, operating means for elevating said cradle, and control means responsive to said gauging means for causing said operating means to center said load relative to said predetermined axis.

9. A power-driven automatic locating gear as claimed in claim 8, said control means comprising a control member, said gauging means be-

ing movable vertically with said cradle relatively to said control member and serving to actuate said control member to control said operating means.
